UNITED STATES PATENT OFFICE.

GLENN MORE, OF JAMESTOWN, NEW YORK, ASSIGNOR TO BLACKSTONE MANUFACTURING COMPANY, OF JAMESTOWN, NEW YORK, A CORPORATION OF NEW YORK.

CLAMP.

1,342,563.

Specification of Letters Patent.

Patented June 8, 1920.

Application filed August 13, 1919. Serial No. 317,106.

To all whom it may concern:

Be it known that I, GLENN MORE, a citizen of the United States, and a resident of Jamestown, in the county of Chautauqua 5 and State of New York, have invented certain new and useful Improvements in Clamps; and I do hereby declare that the following is a full, clear, and exact description thereof, reference being had to the accompanying drawings, and to the letters of 10 reference marked thereon, which form a part of this specification.

This invention relates to improvements in clamps and more especially to a clamp 15 adapted for use on a washing machine or similar device for holding down the lid or cover.

My improved clamp can be easily and 20 cheaply made, since the parts are cast and require no machining or difficult assembly. My clamp is also so designed that it can be attached readily to a washing machine or other device, and is so constructed that it 25 may be operated easily, and will give a maximum clamping efficiency with a minimum effort.

In that form of a device embodying the 30 features of my invention, shown in the accompanying drawings:

Figure 1 is a view in front elevation, of 35 a washing machine with my improved clamp attached.

Fig. 2 is a vertical sectional view on the 40 line 2—2 of Fig. 1, looking in the direction indicated by the arrows.

Fig. 3 is a view in perspective of the 45 journal part of the clamp adapted to be attached to the lid of a washing machine.

Fig. 4 is a view in perspective of the 50 filler block constituting part of the clamp.

Fig. 5 is a view in perspective of the catch 55 part of the clamp adapted to be attached to the body of a washing machine.

Fig. 6 is a view in perspective of the 60 rotatable bolt constituting a part of the clamp.

Fig. 7 is a fragmentary view in perspective of a modified form of the journal part 65 of the clamp.

Fig. 8 is a view in front elevation of a 70 modified form of the catch part of the clamp.

As shown in said drawings, A indicates 75 in general a washing machine of usual construction consisting of the body portion

1 and the hinged lid 2. My improved clamp consists in general of four parts, indicated by the letters B. C. D and E. B indicates the journal part adapted to be attached to the lid of the washing machine. 60 C is the catch part adapted to be fastened to the body portion of the washing machine. D is a rotatable bolt adapted to engage with the catch part C on the body of the washing machine. E is a filler block 65 adapted to fit into the journal part B in order to furnish a more perfect journal for the rotatable bolt D.

The journal part B has a triangular flattened portion 5 adapted to be attached 70 to the lid 2 by means of the screws 6, 6, inserted through the holes 7, 7. The part B projects beyond the edge of the lid 2 and has at its outer extremity a thickened part 3 depending below the upper surface 75 of the lid 2. Extending vertically through the part 3 is a substantially circular hole 8 open along its inner side. The upper end of the vertical opening 8 has opening into it the square hole 9.

The rotatable bolt D is provided with the rounded part 11 adapted to journal in the vertical opening 8 in the part B. At 80 its upper end the bolt D is provided with the shoulder 12 and cross handle 10. Near 85 its lower end it is provided with the shoulder stop 16, and has its lower end bent at right angles to form the hook 13. The bolt D is adapted to be inserted in the hole 8 in the part B by turning the hook 13 so 90 that it will go through the square opening 9 and pushing the same downward until the shoulder 12 lies on the upper edge of the part B. The bolt may then be turned until the hook 13 extends outwardly, or 95 away from the flattened triangular part 5, until the shoulder stop 16 lies under the bottom edge of the vertical opening 8. When in this position, the filler block E is inserted in the part B in order to provide 100 a more perfect journal for the bolt D, as hereinafter described.

The filler block E has its front face concaved as indicated by 15 to conform to the curvature of the rounded part 11 on the bolt 105 9. The curved face 15 of the part E is substantially the same length as the rounded part 11. The upper part of the filler block E is squared as indicated by 17 and adapted to fit into the square opening 9 in the part B. 110

Below the squared part 17 is a square projecting shoulder flange 24 adapted to fit in a corresponding enlarged recess in the part B, below the square opening 9, indicated in Fig. 2 by 21. The lower edge of the part E is adapted to lie in the same plane with the lower edge of the part 3 on the journal part B when the filler block is in place. After the bolt D has been inserted in the hole 8 of the part B and turned until the hook 13 extends outwardly, the filler block E is inserted into the part B so that the squared part 17 lies in the square hole 9 and the shoulder 24 lies in the recess 21. When in this position, the concave face 15 of the filler block E together with the circular part of the opening 8 forms a vertical circular hole affording a journal for the rounded part 11 of the bolt D. The shoulder 12 prevents the bolt D from moving downward and the shoulder stop 16 operating against the lower edge of the filler block E and lower edge of the part 3 on the journal part B prevents the bolt D from moving upward. The lower part of the filler block E is cut away as indicated by 23 to accommodate the edge of the lid 2 of the washing machine. When the bolt D and the filler block E are in place in the journal part B this part is fastened to the lid of the washing machine as shown in Fig. 2 with the edge of the lid projecting into the cut away part 23 of the filler block E. It will be evident that when the part B is firmly screwed onto the lid, the edge of the lid in the recess 23 of the filler block E will hold such filler block in place.

The catch part C of the clamp is a substantially square shaped casting, with a square recess 18 in the center and a segmental tapered catch 19 at its upper edge formed around the semi-circular recess 25. This part is adapted to be fastened to the body 1 of the washing machine below the part B by means of the screws 20, 20, in the holes 22, 22. The parts are so arranged that as the lid 2 is closed the recess 25 will accommodate the shank of the bolt D when the hook 13 is turned outwardly. After the lid is closed, the bolt D is rotated, bringing the hook 13 into engagement with the thin end of the tapered catch 19 on the part C. Further rotation of the bolt D will move the hook 13 across the segmental tapered catch 19 toward its thickened end, thus pulling down the lid 2 and clamping it securely.

Fig. 7 shows a modified form of the device in which the thickened projection 3 of the journal part B is provided at its lower edge with a stop 75 adapted to be engaged by the shoulder stop 16 on the rotating bolt D so that when the bolt 13 is turned outwardly as the lid is closed, the stop 16 will be in engagement with the edge 76 of the stop 75, preventing rotation of the bolt D in one direction. It is obvious that with such a stop

the bolt D must be rotated in one direction only which will bring the hook 13 into engagement with the proper end of the tapered catch 19; that is, with its thin end, so that upon further rotation of the bolt D, the hook 13 will be moved across the catch 19 toward its thickened end, thus clamping and securely holding the lid. The general object of the shoulder 75 is to prevent an attempt to rotate the bolt D in the wrong direction. If it were not for this stop 75, an ignorant operator might turn the bolt D in the wrong direction and attempt to bring the hook 13 into engagement with the thick end of the catch 19 first. The opposite edge 77 of the stop 75 will engage with the shoulder stop 16 on the bolt D and prevent too far rotation, in the event that parts have become worn or loosened to such an extent that sufficient force would operate to rotate the bolt D to such an extent that the hook 13 would move across the entire surface of the tapered catch 19 and slide off of its thickened end, thus again releasing the clamp.

In Fig. 8 I have shown another modification of my device in which the catch 19 on the part C is not tapered from one end to the other, but is thin at each end as indicated by 81, 81, and has its thickest part in the center as indicated by 82. When the part C is formed in such a manner the hook 13 may be brought into engagement with the catch 19 from either end first. In other words, after the lid is closed the bolt D may be rotated in either direction to operate the clamp, the hook 13 engaging with the catch 19 at either end, 81, and drawing up on the thickened part 82 at the center. It is obvious that in the use of this modification the modification shown in Fig. 7 with the stop 75 should not be used, since the bolt must be free to rotate in either direction.

I claim as my invention:

1. In a clamp, the combination of a part with a segmental tapered catch, a journal part, a filler block held in position by said journal part and a rotatable bolt extending through said journal part and having a hook adapted to engage the catch.

2. In a clamp, the combination of a journal part, a filler block in co-operative engagement with said journal part to form a complete journal, a bolt rotatable positioned in said journal and a catch adapted for engagement by the rotatable bolt.

3. In a clamp, the combination with a rotatable bolt provided with a hook, of a journal part forming a journal for one side of the bolt, a filler block forming a journal for the other side of the bolt and a tapered catch adapted to be engaged by the hook on the bolt.

4. In a clamp, the combination of a part circumferentially forming a portion of a journal, a rotatable bolt provided with a

hook, a filler block having a portion adapted to coöperate with said journal part in circumferentially forming the opposite portion of the journal for said bolt, and a segmental tapered catch adapted to be engaged by the hook on the bolt.

5. In a clamp, the combination of a journal part, a rotatable bolt, a filler block adapted to coöperate with said journal part to form a journal for the rotatable bolt, means carried by the journal part for holding said filler block in place, and a bolt catch adapted for engagement by said bolt.

10. In a clamp, a bolt, a journal part provided with means affording one side of the bolt journal, a filler block held in position by said journal part and provided with means forming the other side of the journal, and a catch adapted for engagement by said bolt.

15. In a clamp, the combination, with a rotatable bolt, of a filler block forming a portion of a journal for said bolt, a journal part surrounding said filler block and forming the other portion of the journal for the bolt, and a catch adapted for engagement by the bolt.

20. In a clamp, the combination with a rotatable bolt and a catch adapted for engagement thereby, of means forming a segmental portion of the journal for said bolt, said means inclosing a member forming the complementary segmental portion of said journal.

25. In a clamp, the combination with a rotatable bolt and a catch adapted for engagement thereby, of means forming a segmental portion of the journal for said bolt, said means inclosing and retaining in position a member forming the complementary segmental portion of said journal.

30. In a clamp, the combination of a journal part with an opening therethrough, a rotatable bolt with a hook adapted to be inserted through said opening, a filler block adapted to coöperate with said journal part to form a journal for said bolt, and a tapered catch adapted to be engaged by the hook on the bolt.

35. In a clamp, the combination of a journal part with an opening therethrough, a rotatable bolt with a hook adapted to be inserted through said opening, a filler block adapted to coöperate with the journal part to form a journal for the bolt, means for holding the filler block in place, and a segmental tapered catch adapted to engage with the hook on the bolt.

12. In a clamp, the combination of a journal part with an opening therethrough, a 60 rotatable bolt adapted to be inserted through said opening, a filler block adapted to coöperate with the journal part to form a journal for the bolt, means to limit the rotation of the bolt, and a bolt catch. 65

13. A clamp comprising a bolt catch mounted on a fixed support, a journal member mounted on a movable part, a circular opening therethrough forming a part of a vertically disposed bolt journal, a recess 70 communicating with said opening, a filler block in said recess having a concave face adapted to act as part of the bolt journal, a bolt rotatably mounted in the journal member and projecting beyond it at each 75 end, a locking part on the bolt adapted for operative engagement with the catch, and means for limiting the vertical movement of the bolt in its journal.

14. A clamp comprising a bolt catch 80 mounted on a fixed support, a journal member mounted on a movable part, a circular opening therethrough forming a part of a vertically disposed bolt journal, a recess 85 communicating with said opening, a filler block in said recess having a concave face adapted to act as part of the bolt journal, a bolt rotatably mounted in the journal member and projecting beyond it at each end, a locking part on the bolt adapted 90 for operative engagement with the catch, and means for limiting the rotative movement of the bolt.

15. A clamp comprising a bolt catch 95 mounted on a fixed support, a journal member mounted on a movable part, a circular opening therethrough forming part of a vertically disposed bolt journal, a recess 100 communicating with said opening, a filler block in said recess having a concave face adapted to act as part of the bolt journal, a bolt rotatably mounted in the journal member and projecting beyond it at each 105 end, a locking part on the bolt adapted for operative engagement with the catch, means for limiting the vertical movement of the bolt in its journal and means for limiting the rotative movement of the bolt.

In testimony that I claim the foregoing as my invention I affix my signature in the 110 presence of two witnesses, this ninth day of August, A. D. 1919.

GLENN MORE.
